UNITED STATES PATENT OFFICE.

CHRISTOPHER F. DONIGAN, OF NEWARK, NEW JERSEY.

HEEL.

Application filed December 30, 1921. Serial No. 525,832.

To all whom it may concern:

Be it known I, CHRISTOPHER F. DONIGAN, a citizen of the United States, and a resident of Newark, county of Essex, and State of New Jersey, have invented certain new and useful Improvements in Heels, of which the following is a specification.

This invention relates to an improved heel made of resilient material, usually rubber, which can be quickly attached and detached, and which can thus be made interchangeable from one shoe to another, so that when worn on one edge the heels can be interchanged so as to cause wear on the other edge.

The invention relates further to a heel which can be utilized in two positions on the same shoe; so that in use on two shoes four points of excess wear can be utilized.

The invention also relates to a heel of this kind which can be disposed so as to form a support for the arch of the foot and thus provide more comfort for people with this form of foot weakness.

The invention is illustrated in the accompanying drawing, in which Figure 1 is a perspective view of a heel and one form of attaching means. Figure 2 is a section through a heel and the heel portion of a shoe. Figure 3 is an enlarged detail section of a part of a heel and an attaching means. Figure 4 is a perspective view illustrating one way of releasing the heel from the shoe, and Figure 5 is a top view of a form of heel different from that shown in Figure 1.

The heel is designated by the reference numeral 10 and may be made of any suitable resilient material, and I prefer to use rubber, now commonly used in heels, and to secure a maximum of resiliency the heel is usually made entirely of rubber. The nature of the material provides an easy cushion effect when the heel is trod on in walking, and the resiliency also permits a lateral compression of the heel, and particularly it permits a somewhat extensive local distortion or compression of the heel where attaching means are secured. This is utilized in yieldingly holding catches or the like in holding or locking position, and also permits their intentional displacement from such locking position so that the heel can be removed.

One form of attaching means is illustrated in the drawing, which shows a series of catches 11 which are in the form of pegs and which project from the top face of the heel and extend with hooked portions or

engaging ends 12 which project outward radially, that is, toward the outer edge of the heel so that they can be moved laterally, thus subjecting the material at this point to a slight distortion, which, of course, is relieved, and the material assumes its normal shape when such lateral pressure is relieved.

These catches 11 are usually provided with a shank 13, and a broadened head 14 is placed on the inner end and, being embedded in the material of the heel, provides for a positive holding of the peg or latch in the heel. It will be evident that these catches can be caught over properly disposed holding edges, and in the form shown I provide a plate 15 preferably in the form of a frame which has on its inner edge the parts 16 which are spaced apart in conformity with the spacing of the catches 11.

It will thus be evident that when the plate 15 is fastened to a shoe, either to one of the upper layers of a heel or to the bottom part of the shoe at the heel in any suitable manner, usually by nails or pegs driven through holes 17 for the purpose, the heel can be attached by simply pushing it against the plate enough to cause the catches 11 to ride over the edges 16 and be hooked in position.

To prevent lateral strain on the pegs in any excessive degree, I prefer to use anchoring devices, which may be in the form of lips 18 which project down in similarly disposed recesses 19 in the heel, although any similar or equivalent means for so anchoring the heel against lateral movement can be employed.

When the heel is to be removed it can be done by the insertion of an element laterally along the top edge or face of the heel and the pegs successively disengaged, pressing them radially inward, and in Figure 4 I show a convenient method of moving them inward simultaneously by means of a thin wire or cord 20 which is crossed and then pulled in the form of a closed loop along the top face of the heel, and such wire or cord will then take the position shown in Figure 3, and when tightly pulled will pull all the pegs radially toward the center, as shown in said figure, and the heel can be lifted away from the shoe.

To act as a positive guide and prevent the destruction of the wire 20, I prefer to place a marginal flange 21 on the edge of the plate 15, which serves not only to more securely

hold the plate against lateral movement, but also to provide a positive means for guiding the wire 20 between the plate 15 and the top face of the heel.

5 In Figure 5 I show a top view of a heel of a normal form with the pegs 11 disposed for attachment of such shape of heel to a shoe.

The form of heel shown in Figures 1, 2 and 3 is designed for the purpose of being 10 placed end for end on the same shoe when uneven wear is to be compensated for, and also to serve as a shank support. This heel is usually designed to extend a material distance forward of the front edge of the shoe 15 heel, which line of the shoe heel is indicated at *a* in Figure 2.

It will be noted that the heel has its end rounded to conform to the rear outline of the heel of a shoe, so that the heel can be 20 taken off and the front swung around to the back and the heel replaced, which makes it possible to take up the uneven wear, which is usually on the outside rear corner of the heel; so that diagonally opposed points can 25 be worn down with the heel on the same shoe, and then by transferring the heels from one shoe to the other the opposed corners can be worn down, so that four points 30 of wear are available and thus a longer life is provided for each heel.

In addition, this form of heel makes it possible to have the forwardly projecting part, which is beyond the normal heel line, act to 35 sustain the shank of the shoe in front of the normal heel line, making it a desirable article for use by people who have foot troubles requiring such support.

I claim:

1. A heel made of resilient material, 40 catches on the top face of the heel, and se-

curing means disposed so as to receive the catches and hold the heel in place, the tops of the catches being formed so as to cause the heel to be distorted and the catches snapped into place in the securing means 45 when pressure is applied to the bottom of the heel.

2. A heel made of resilient material, catches on the top face of the heel, and securing means disposed so as to receive the 50 catches and hold the heel in place, the tops of the catches being formed so as to cause the heel to be distorted and the catches snapped into place in the securing means 55 when pressure is applied to the bottom of the heel, said catches being arranged so that they face outwardly from the center of the heel, whereby they can be released by a radially and inwardly directed pressure on the side walls of the heel. 60

3. A heel made of resilient material and having outwardly extending catches projecting from its top face, and having recesses in its top face, and a frame having its inner edge adapted to receive said catches, 65 said frame having lips to enter the recesses of the heel.

4. A heel made of resilient material and having outwardly extending catches projecting from its top face, and having recesses in its top face, and a frame having its inner edge adapted to receive said catches, 70 said frame having lips to enter the recesses of the heel, and said frame having an upwardly turned marginal flange. 75

In testimony that I claim the foregoing, I have hereto set my hand, this 7th day of December, 1921.

CHRISTOPHER F. DONIGAN.
